E. Baker
Cotton Picker

Patented Jun. 4, 1830.

June 4, 1830

Elisha Baker

SACRED PATENT

The Schedule referred to in the certificate of Patent and making part of the same containing a description in the words of the said Elisha Baker himself of his improvement called the Revolving Cotton and whipper.

The essential principle or plan or principle of the Revolving Cotton whipper, and which distinguishes it from the common Cotton whipper consists in the rotary motion and the machinery connected with this motion and especially constituting the improvement, are two vertical cylinders placed near each other, each cylinder being covered with projecting points, and these points being so placed on the cylinders that when the cylinders revolve the points on the respective cylinders will meet and pass each other. The machinery is made of such materials as are commonly used for like purposes, and is secured to framework, closely enclosed in a frame or case, and is put in motion by water, steam, animal or other power of pleasure.

The different parts of the machinery embraced by this improvement are particularized as follows, viz. The parts which are first put in motion, are the cylinder shafts. These shafts, placed upright or in a vertical position should be of iron, four feet more or less in length, and of sufficient strength having one end pointed and a spur or cog wheel of suitable dimensions, attached to the other or open end. The shafts have each of them a bearing or journal turned upon them, a few inches only from the cog wheel, and each of these shafts is fixed longitudinally in the centre of a cylinder that is three feet more or less in length and one foot more or less in diameter. The pointed end of the shaft projecting a few inches only from the cylinder. The cylinders may be of wood, they should be of uniform diameter, and must be turned from one end to the other with long projecting points, called whipping sticks, which ought to be of iron wire or other strong materials. The whipping sticks

should be round and smooth, and they must be firmly secured by one end to the cylinders from which they may project somewhere about twelve or eighteen inches, and their direction must be horizontal or at right angles with the surface of the cylinders. There may be more or less of these whipping stocks in each cylinder, but when inserting these stocks, care should be taken to place them in a spiral direction around the cylinder from one end to the other of it, and they must be placed at such distance from each other, as to leave around the cylinder a horizontal space rather more than equal to the size of one of the stocks. This may be accomplished by making around the cylinder fourteen, more or less, horizontal circles, at equal distances from each other, taking care that the space between the circles, be rather larger than a whipping stock, then insert a whipping stock in every other circle on the one cylinder, and in the corresponding intermediate circles on the other cylinder, observing to place the whipping stocks spirally, from one end to the other of the cylinder. The cylinder shafts complete with gear, cylinders & whipping stocks, are to be stationed by the side of, parallel with, and so near to each other, that the points of the whipping stocks on the one cylinder will nearly touch the other cylinder itself. The shafts are to be kept in this position by a frame of wood or other material. The frame is composed of several pieces well secured to each other, two of which are called the upright posts. The upright posts stand perpendicularly on the floor of the building are six or eight feet high, and stationed at the proper distance, say four feet, more or less, from each other, and they are confined to each other by one piece which extends from the one to the other post, and this piece, are called girts. The girts are four or less in number, one is at the top end of the posts, another is at the bottom end of the posts, and the remaining two girts, being the most important ones are fixed near the center of the post.

within the other girls, and correspond in distance from each other, with the points and journals of the cylinder shafts. The upper girl is called the top girl, and the next girl is called the middle girl. The girl below that is called the step girl, and the lowest girl is called the bottom girl. At the part opposite with the middle girls are placed metallic or other boxes for the reception of the ends or bearings of the cylinder shafts, and at corresponding places on the step girl are secured the steps (made of metal or with an appropriate substance) for the reception of the pointed ends of the cylinder shafts. The boxes and steps keep the cylinder shafts in their relative positions, and at the same time should permit them to revolve freely on their axes. The cylinder shafts are to be fast in and driven by a third shaft having a cog wheel on one end of it which cog wheel is called the first wheel, and fits the cog wheels on the cylinder shafts. The third shaft is called the driving shaft, and it is secured to the top girl, and to the middle girl and is situated between the cog wheels of the cylinder shafts having its cog wheel playing in the cog wheels of the cylinder shafts. A pulley is secured on the lower or upper end of the driving shaft and is called the driving pulley. A cage of wood tin or other suitable substance surrounds the two cylinders. This cage is called the cub. The cub has a small opening at the top of it through which the cotton is put to enter among the whipping sticks. The cub has also an opening at the lower part of it, on one side, when the cotton after it is whipped comes out. At the bottom of this cub are gates of wood which form the flooring of the cub. Through these gates the dirt from the cotton falls into the drawer. The drawer is as large as the bottom end of the cub. It occupies the space between the top girl and the bottom, and is made to be taken out at pleasure by rings, knobs, or handles fixed on the side. The operation of the spinning cotton whipper is as follows, by power being applied by means of a belt to the pulley on the driving shaft. The two cylinders are put in motion. The cotton is introduced among the whipping sticks through the hole in the top of the cub, and the cotton may be put motion of the whipping sticks or by own weight pass through the cotton and be whipped through the opening at the bottom part of the cub. (See the diagram) 1136
